UNITED STATES PATENT OFFICE

JOHN McPHERSON COOKE, OF BEACHMONT, MASSACHUSETTS, ASSIGNOR TO NICHOLAS W. MATHEY, OF LYNN, MASSACHUSETTS

TRIMMING MACHINE

Application filed October 18, 1928. Serial No. 313,214.

This invention relates to trimming machines in general, and more particularly to the type used in the manufacture of shoes. The embodiment illustrated is especially adapted to trimming the lining from panels which have been previously cut in the shoe upper to form a design or for any other purpose.

In the manufacture of shoes employing modern methods the time factor is most important. One of the important objects of this invention is to provide means to speed up production.

Another object of the invention is to provide a trimming machine upon which accurate work may be done by an unskilled operator.

A further object is to provide a machine which will trim the article neatly and thoroughly in the most inaccessible places such as an acute angle corner which may be part of an intricate design.

A further object of the invention is to provide a machine which will trim smoothly all concave or convex curves a feature which is very important and one which is lacking in many types of trimming machinery.

A further object of the invention is to provide a machine in which the various controlling mechanisms necessary to start, to execute, and to stop the trimming operation, may be operated from a single controlling element.

Other objects and features will more fully appear from the following description in connection with the accompanying drawings and will be particularly pointed out in the claims.

In the drawings:

Fig. 1 is a view in elevation of the head of a machine looking from the left with a cover plate removed.

Fig. 2 is a vertical cross-section on line 2—2 Fig. 1.

Fig. 3 is a general front elevation of a machine with the pedestal partly broken out.

Fig. 4 is a detail view of a detachable guide-frame which constitutes part of the head of a machine.

Fig. 5 is a vertical sectional view on line 5—5 Fig. 4.

Fig. 6 is a detail perspective view showing the construction and relative positions of the

work support, the cutter, and cutter guard.

Fig. 7 is a section on line 7—7 Fig. 6 looking down upon the work support.

In order to present a full and clear conception of the invention a specific form of the machine is herein illustrated in which the principles of the invention are embodied. It is to be clearly understood however that the invention is not restricted to the particular embodiment shown. The principles of the invention may be adapted to trimming machines of various types which are employed for trimming various articles or for various parts of a particular article.

There is a broad field of usefulness to which the invention is adapted. The following are a few of the operations in which the invention may be advantageously employed. Trimming the lining projecting from the top edge of the upper on a shoe after it has been lasted. Trimming all vamps after the completion of lasting operations or in trimming the lining from panels which have been previously cut in the shoe upper. It is in the latter operation that the embodiment herein disclosed is employed. The shoe designer quite frequently resorts to panelling in order to produce a pleasing design. A panel as it is known in the art of making shoes is a portion of the upper which is cut away, but which is entirely within the borders of the shoe upper. The usual practice is to cut the panels before the various parts of the upper are incorporated into the shoe, and to sew the lining to the upper along the border, and close to the edge of the panel leaving the lining uncut at the panels. The parts are then assembled into a shoe leaving the operation of trimming out the sections of the lining which obstruct the panels to be done on the type of machine herein disclosed.

The embodiment chosen for the purpose of illustration comprises a main frame 1 which includes the pedestal 2. A rigid bracket 3 is secured to the pedestal 2 and has at its end a hollow boss 4 in which is journaled the lower end of a horn or U-shaped member 5 to swing about a vertical axis which is in alignment with the center of work 100

support 6 that is upon the free end of the horn. By reason of the ability of the horn to rotate, the operator may hold the work in any position without obstruction. This construction however necessitates a special design of work support which will hereinafter be more fully described.

The cutting mechanism comprises a vertically reciprocating knife 7 which co-operates with an annular shaped shearing-blade 8 of hardened steel at the inner edge of the work support 6, thereby to sever the material. The center of the shear blade 8 coincides with the axis about which the horn swings and the knife 7 is positioned to engage the shear-blade to properly perform the trimming operation at any position of the horn. The knife 7 must be curved slightly to conform to the curvature of the shear-blade as shown at 9. It will thus be seen that throughout the operation of trimming the shoe the knife may be acting at various points upon the shear-blade, but a proper shearing relation between the knife and the shear-blade is always maintained. In order to support the work which extends transversely across the annular-shaped blade 8, a disc shaped member 10 may be arranged and mounted resiliently within the shear-blade 8, said member 10 being of such a size that when the knife 7 is interposed between the disc 10 and the shear-blade 8 the disc will be slightly deflected to one side of the center. However, under usual conditions the disc member 10 may be omitted.

The main frame 1 is of usual form having an overhanging portion 11 at the end of which is a recessed head 12 in which is located the major portion of the driving mechanism. It is essential to the proper functioning of the machine that the knife 7 be kept in accurate alignment with the annular shear-blade 8. Means are provided herein to accomplish this result at a minimum of cost. The knife 7 is secured to a cutter bar 13 of circular cross-section which has a bearing in a removable guide-frame 14 and in which it is vertically reciprocated by means which will be herein-after set forth.

It is an accepted fact that a more accurate bearing can be made to receive a slide of circular cross-section than one of any other shape and at much less expense. In order to maintain the high efficiency of the bearing thus produced it is desirable that the bearing be made of some wear-resisting material other than the usual grade of iron out of which the frame of such machines are made. To provide the material for the bearings it is merely necessary to make the guide-frame out of wear-resisting material and machine the bearing directly therein. A more expensive material may be used therefore out of which to make this relatively light section of the frame. Furthermore this small section

of the frame may be made at a different establishment than that in which the rest of the machine is made in which highly developed special machinery may turn them out in large quantities and at a greatly reduced cost. At any rate this section of the frame which constitutes the heart of the machine, being of a comparatively small and easily handled character, may be constructed upon a jig or special machine that is relatively light and inexpensive and at the same time such special machine will be capable of maintaining a high degree of accuracy in the finished product. This guide-frame may be fastened to the head 12 in any suitable way as by screws 15.

Co-operating with the cutter is a cutter guard 16 which serves as both a guard to prevent injury to the operator and also as a guide to the operator to follow the edge of the work as it is fed to the cutter. This cutter guard is mounted on a supporting bar 17 journaled in the guide-frame 14 and parallel to the cutter bar 13 and in such a manner that it may have longitudinal movement therein. Extending at right angles from and secured to the bar 17 near its upper end is a stud 18 which passes through a vertical slot 19 in the guide-frame 14. A compression spring 20 is seated at one end in a recess 21 in the guide-frame and bears at its other end upon the upper end of the bar 17 tending normally to press the bar downwardly. A manually operable lever 22 is pivoted upon the head 12 at 23 and extends beneath the stud 18 and is limited in its downward movement under the action of the spring 20 by an adjustable stop screw 24. The guard 16 may therefore be set at any desired height above the work support by adjusting the stop screw 24. By means of the hand lever 22 the guard may be raised by the operator to avoid any obstruction on the work as it is fed past the cutter after which the spring 20 will act to restore the guard to its adjusted position.

The cutter bar may be reciprocated in any manner but is herein shown as operated from an eccentric 25 upon a drive shaft 26 journaled horizontally in the main frame. The shaft 26 may be directly connected to an electric motor or driven from a belt upon a pulley 27 or in any other suitable manner. The motion of the eccentric 26 is transmitted to the cutter bar in a novel manner. An eccentric strap 28 encircles the eccentric and has a depending arm 29 in the end of which is a cylindrical bearing 30 which receives a stud shaft 31 projecting from a driving block 32 which is loosely mounted upon the cutter bar 13. The driving block 32 has a projection 33 which extends into and has a running fit in a vertical slot 34 in the guide-frame 14. The driving block is thus free to have a vertical movement upon the cutter bar 13 but is prevented from rotation thereupon by the projection 33 130

which is confined to the slot 34. To reduce friction at the driving point an anti-friction bearing 35 is employed between the eccentric and the eccentric strap.

5 During the operation of the machine the shaft 26 is rotating continuously and reciprocates the driving block 32 by means of the eccentric strap. Fixed rigidly to the cutter bar 13 as by the set screws 60 is a block 36 which 10 has a horizontal projection 37 which extends into and has a running fit in a vertical slot 38 in the main frame 12. The cutter bar and cutter are thereby held positively against rotation. Pivoted upon the block 36 at 39 is a 15 clutching lever 40. One arm of the lever 40 extends downwardly and has upon its end a lip 41 adapted to engage the lower edge of the projection 33 upon the driving block 32. A tension spring 42, attached at one end to 20 an arm 43 of the lever 40 and at its other end to the block 36 acts to hold the block 32 clamped between the lip 41 and a shoulder 44 on the block 36. The cutter bar and cutter are thus reciprocated by the block 32.

25 The lever 40 also has a substantially horizontal arm 45 which is situated in the path of one end of a manually operative lever 46 which in turn is pivoted upon the main frame at 47 and is connected at its other end to a 30 foot pedal 48 by a link 49. A slot 50 is provided in the main frame in which the lever 46 moves. It will thus be seen that when the forward end of the lever 46 is raised, as by depressing the foot pedal 48, that it will act, 35 first, to rock the clutching lever 40 thus disconnecting the block 36 from the driving block 32 and, second, to raise the block 36 and therewith the cutter bar.

40 As shown in the drawings the parts are in position to operate the cutter and to accomplish the trimming operation. If it is desired to stop the trimming operation the operator steps on the foot pedal 48 which rocks the lever 46 about its pivot 47 and brings it into 45 engagement with the arm 45 of the lever 40 which results in rocking the lever 40 about its pivot and withdrawing the lip 41 from its engagement with the projection 33 on the driving block 32 and thus disengages the driving 50 block from the cutter bar. The horizontal projection 37 of the block 36 is also in the path of the lever 46 and upon further movement of the latter the projection 37 is engaged and raised thus raising the cutter bar and the cutter. The machine is now in condition to 55 enable the operator to start a new cutting operation or if he desires to cut out a panel it is convenient to also raise the cutter guard. Means are provided to accomplish this by

60 further actuation of the foot pedal 48. At the lower end of the cutter bar 13 a short stud 51 projects horizontally in such a position that upon a predetermined upward movement of the cutter bar 13 it will engage a collar 52 fixed to the cutter guard supporting bar 17

and upon further movement of the cutter bar the cutter guard will be elevated thus providing clearance to place the shoe or other article in position to trim out a panel or any other portion of the work.

70

In order to start the machine and restore the parts to trimming position it is merely necessary to release the pressure upon the foot pedal and a compression spring 53 acting upon the block 36 will lower the block 75 until the shoulder 44 thereon engages the constantly moving driving block 32. As the pressure on the foot pedal is entirely released the lever 40 will be free to rotate under the influence of the spring 42 which will cause 80 the lip 41 to re-engage the projection 33 on the driving block 32; thus clutching the driving means to the cutter bar. As the cutter bar is lowered the cutter guard supporting bar 17, under the action of the spring 20, restores the cutter guard to its proper position and the machine is then ready to assume its trimming operation.

85

It will be noted that the various controlling operations are accomplished while the drive shaft is constantly rotated at high speed. As a consequence of this the operator may start, stop and control the machine without the necessity of starting or stopping the driving motor or manipulating whatever 90 source of power that may be employed to drive the machine. The design of the clutching mechanism is such that the cutter may be instantly accurately and smoothly thrown into and out of operation without excessive 95 wear or strain upon the parts. Furthermore the cutter guard may be thrown into and out of position at any time regardless of whether the cutter is operating or not. Since the cutter guard performs the double purpose of 100 guarding the operator against injury and guiding the work it must be held in accurate alignment with the cutter. The stud 18 which passes through the vertical slot 19 provides the necessary stability for the cutter 105 guard.

100

One of the most valuable refinements of the machine is the high efficiency of the guiding means for the cutter bar. As above pointed out the bearing for the cutter bar is 110 very accurately fitted and designed to resist wear. This construction combined with the positive means of preventing rotation of the bar about its vertical axis insures that the cutter will be guided with absolute accuracy.

115

Having thus described the invention, what is claimed as new, and desired to be secured by Letters Patent, is:

120

1. An edge trimming machine comprising a frame, a work support, a cutter bar of circular cross-section, a cutter mounted thereon, a guide block rigid with the bar and guided in the frame thereby to prevent rotation of the bar about its longitudinal axis, a collar loosely mounted upon the cutter bar and 125

130

guided in the frame to prevent rotation thereof about the bar, driving means acting to reciprocate the collar and means to detachably connect said collar to said cutter bar there-
5 by to reciprocate the same.

2. An edge trimming machine comprising a main frame having a projecting head, a removable guide-frame of wear-resisting material secured to said head, a cutter bar 10 mounted for reciprocation in said guide-frame, a cutter mounted on the cutter bar, a bracket projecting from said main frame, a work support swivelly secured to said bracket, an annular shear-blade mounted on 15 said work support and disposed in cooperative relation to said cutter, said work support being rotatable about an axis concentric with the curvature of said annular shear-blade, driving means in the main frame to 20 reciprocate the cutter bar, and means detachably to connect the cutter bar to the driving means.

3. An edge trimming machine comprising a main frame having a projecting head, a removable guide-frame of wear-resisting material secured to said head, a cutter bar 25 mounted for reciprocation in said guide frame, a cutter mounted on the cutter bar, a cutter guard, a supporting bar mounted in said guide-frame upon one end of which is mounted the cutter guard adjacent to the cutter, a bracket projecting from said main frame, a work support swivelly secured to 30 said bracket, an annular shear-blade mounted on said work support and disposed in cooperative relation to said cutter, said work support being rotatable about an axis concentric with the curvature of said annular shear-blade, driving means in the main frame 35 to reciprocate the cutter bar, and means detachably to connect the cutter bar to the driving means.

4. A machine of the character described comprising a frame, a cutter bar, a cutter 40 mounted thereon, a guide block rigid with said bar and slidably mounted in said frame, a collar loosely mounted about said cutter bar and slidably in said frame, driving means connected to said collar for reciprocating the same, and releasable clutching means carried 45 by said guide block for detachably connecting said collar and cutter bar, whereby said cutter may be instantly thrown into or out of operation.

5. A machine of the character described comprising a main frame having a laterally projecting recessed head, a removable guide-frame of wear-resisting material disposed in the recessed portion of said head, a cutter bar 50 slidably mounted in said guide-frame, a cutter carried by said bar, a guide block rigid with said cutter bar and slidably therewith, a collar slidably mounted about said cutter bar, driving mechanism connected to said collar 55 for reciprocating the same, and releasable

clutching means carried by said guide block for detachably connecting said collar and cutter bar, whereby said cutter may be instantly thrown into or out of operation.

6. A trimming machine of the class de- 70 scribed comprising a main frame having a recessed head, a removable guide-frame secured in said head, spaced bearings in the guide-frame, a cutter bar mounted in the spaced bearings of the guide-frame, a cutter secured to said cutter bar, a fixed bracket projecting from said main frame and spaced from said head, a work support disposed below the head of the main frame, an annular shear blade mounted on said work support and disposed in cooperative relation to said cutter, said work support being swivelly secured to said bracket and rotatable about an axis concentric with the curvature of the annular shear blade, a drive shaft in said frame for 75 reciprocating the cutter bar, and releasable means detachably connecting the cutter bar 80 to the drive shaft.

7. A trimming machine of the class de- 90 scribed comprising a main frame having a recessed head, a removable guide-frame of wear-resisting material secured in said head, spaced bearings in the guide-frame, a cutter bar mounted in the spaced bearings of the guide-frame, a cutter secured to said cutter bar, a fixed bracket secured to the main frame and in spaced alignment with the head of the frame, a U-shaped member swivelly secured to said bracket, a work support secured to the free end of said member, an annular shear blade mounted on said work support and so disposed that its cutting edge registers with that of the cutter, said work support and U-shaped member being 95 rotatable about an axis concentric with the curvature of said annular shear blade, a drive shaft in the main frame for actuating the cutter bar, and releasable means detachably connecting the cutter bar and drive shaft.

8. A trimming machine of the class de- 100 scribed comprising in combination a reciprocating cutter bar, a cutter secured to said cutter bar, a work support, an annular shear blade mounted on the work support so that the cutting edge of the cutter registers with that of the shear blade, said work support being rotatable about an axis concentric with the curvature of the annular shear blade, a drive shaft, and transmission mechanism 105 associated with the drive shaft and cutter bar for reciprocating the latter, said mechanism comprising a rigid member disposed transversely of the cutter bar and rigidly secured thereto, a movable abutment engageable with the rigid member, means carried by the latter member urging the abutment into engagement with the rigid member, and means connected with the drive shaft for imparting a reciprocatory motion to the movable abutment thereby to reciprocate the cutter bar. 110

9. A trimming machine of the class described comprising in combination a reciprocating cutter bar, a cutter secured to said cutter bar, a work support, an annular shear blade mounted on the work support so that the cutting edge of the cutter registers with that of the shear blade, said work support being rotatable about an axis concentric with the curvature of the annular shear blade, a drive shaft, and disengageable transmission mechanism associated with the drive shaft and cutter bar for reciprocating the latter, said mechanism comprising a rigid member disposed transversely of the cutter bar and affixed thereto, a movable abutment engageable with the rigid member, releasable means carried by the latter member urging the abutment into engagement with the rigid member, means associated with the drive shaft for imparting a reciprocatory motion to the movable abutment thereby to reciprocate the cutter bar, and means engageable successively with the releasable means and with the rigid member for releasing the abutment and for raising the cutter bar.

In testimony whereof, I have signed my name to this specification.

JOHN McPHERSON COOKE.
